[57] ABSTRACT

A holder for an inking pad is provided which is removably mountable on a manually operated printing stamper; the holder consists of a rectangular sheet of flexible material having notches cut out adjacent each of its corners and a rectangular slot positioned equidistantly from its upper and lower edges; the dimensions of the sheet are such that it may be bent into an arcuate shape and the notches positioned in engagement with the frame of the stamper whereby, due to its resilience, the holder will be maintained in engagement with the frame of the stamper; a felt inking pad is inserted through the slot of the holder so that a portion of the pad intersects the path of the printing elements of the stamper so that when the printing elements are actuated to move through the path, they will come into contact with the inking pad to receive a coating of ink.

PRICE STAMPER AND STAINLESS STEEL PAD HOLDER

BACKGROUND OF THE INVENTION

The present invention relates to improvements in self-inking hand stampers and, more particularly, to a novel inking pad holder arrangement.

In many retailing outlets, where large quantities of different priced articles are vended, it has been found desirable from the point of view of efficiency to print the price on each article to reduce the checking out time of each customer and to enable the cashiers to quickly and accurately record the price of each article in totaling up the charge to the customer. Manual price stampers of the self-inking type have been widely used in such outlets to affix the prices on the various articles. Such stampers have generally consisted of two frame members one of which is movable with respect to the other, and the other of which is first placed in contact with the article to be priced. The movable frame is usually provided with a printing element carrier which consists in a plurality of flexible belts having printing indicia formed thereon. The carrier is generally arranged so that the printing indicia are maintained under a constant spring force in contact with an inking pad so that, when the stamper is actuated, the printing elements on the distal end of the carrier move through a generally arcuate path into engagement with the article to be stamped. Subsequently, the printing carrier returns to its original position with the printing elements in engagement with the inking pad. The ink which is generally used with such stampers is of the quick drying, indelible type so as to prevent smearing or erasure of the price once it is affixed to the article.

While such price stampers have enabled retailers to rapidly affix different prices to a large number of discrete articles, certain inconveniences and difficulties have been encountered with respect to the handling and operation of the inking pads used in the devices of the prior art. More specifically, in some of the stampers presently in use, as a result of the constant spring force with which the printing elements are pressed into the inking pad when the stamper is not in use there has resulted the formation of indentations in the pad of the shape of the indicia that happen to be located on the distal end of the printing carrier. As a result, when different indicia are placed in the printing position, the latter indicia are not evenly coated with ink thus often rendering the marking illegible.

Moreover, the pad holders of the prior art have generally been positioned in the frame of the stamper so that the application of ink thereto has been a difficult and often messy operation. In still other arrangements, it has been necessary to first remove the pad completely from the frame in order to supply the pad with ink. An additional difficulty with the ink pads of the prior art has been the problem of seepage of ink from the pad onto the printing bands which, due to the nature of the ink employed, has resulted in the sticking of the bands to each other and to their carrier when the ink dried. Quite frequently, breakage of the bands resulted when pressure was exerted upon these bands to loosen them. Furthermore, due to the fact that the inking pads have generally been encased in a holder, the pads have had a tendency to become quite hard and brittle thus rendering them altogether useless.

The prior art solutions to the foregoing problems have generally involved the addition of elaborate and often complicated pad holding arrangements to existing price stampers which has contributed substantially to the manufacturing costs of the stampers as well as required an increase in the number of moving parts which are subject to wear and breakage.

The present invention avoids all the foregoing disadvantages by providing an inking pad holder which can be inexpensively adapted to cooperate with a large variety of price stampers and which will function much more reliably than the arrangements which have heretofore been proposed.

SUMMARY OF THE INVENTION

The inking pad holder of the present invention consists in a rectangular plate constructed from a resilient material such as spring treated stainless steel. A slot is provided at approximately the midpoint of the plate and which extends substantially parallel to the edges of the plate that are attached to the frame of a conventional price stamper. The dimensions of the slot are such that a flexible pad of felt material may be inserted into the slot to be frictionally engaged by the edges of the slot. With the price stampers of the type where the printing element moves through a substantially semicircular path when the stamper is actuated, the pad holder is positioned on the frame so that a portion of the inking pad will be positioned at a point intersecting the path of travel of the printing element. The dimensions of the inking pad are chosen so that all of the printing indicia on the printing element will be contacted by the inking pad as the element travels through its arcuate path.

With the foregoing arrangement, the useful life of the inking pad is substantially prolonged and will function to supply ink evenly to all of the printing indicia on the printing bands of the stamper.

It is a principal object of the present invention, therefore, to provide an inking pad holder that can be quickly and easily positioned on the price stamper and which can be easily supplied with printing ink.

Another object of the present invention is to provide an inking pad holder which will maintain the inking pad in a position where ink will be supplied to the printing elements uniformly over a prolonged period of use. Another object of the present invention is to provide a pad holder that so positions the pad that it will not be subjected to a constant pressure from printing elements in contact therewith when the price stamper is not in use.

A further object of the present invention is to supply an inking pad holder that will operate to provide clearly printed characters throughout a much larger number of printing operations.

A still further object of the present invention is to provide an inking pad holder that will permit easy and thorough cleaning of the price stamper.

Another object of the present invention is to provide an inking pad holder that is extremely simple and inexpensive to manufacture.

These and other objects and attendant advantages will become apparent as further consideration is given to the following detailed description together with the accompanying drawings, in which:

BRIEF DESCRIPTION OF THE DRAWINGS

FIG. 1 is a side view in elevation of a conventional

manually operated price stamper to which the pad holder of the present invention is attached illustrating the disposition of elements in a partially actuated position.

FIG. 2 is a front view in elevation, partly in section of FIG. 1 but with the stamper in an unactuated position; and

FIG. 3 is another embodiment of the inking pad holder of the present invention.

DETAILED DESCRIPTION OF THE INVENTION

Referring now to the drawings, there is illustrated in FIG. 1, a conventional manually-operated stamper generally designated at 10 which consists of a base frame generally designated at 12 and a movable frame indicated at 14.

The base frame 12 has a pair of side members 16 and 18, a top cross member 20 and a bottom plate member 22 which is formed with a substantially rectangular opening (not shown) through which the printing elements pass on the downstroke of the stamper 10. On either side of the opening in plate 22 on the exterior face thereof, there are provided pads 24 and 26 which engage the surface 28 on which indicia are to be printed.

Referring to FIG. 2, a shaft 30 is secured to the top of cross member 20 of base frame 12 and extends upwardly therefrom.

The movable frame 14 consists of side members 32 and 34 which are connected by a cross member 36. Member 36 has an aperture 38 through which shaft 30 extends. On the top side of member 36 there is secured a hollow, tubular handle 40, disposed concentrically about aperture 38. A coil spring 42 is located inside handle 40 with one end of the spring abutting the closed end of handle 40 and with the lower end of the spring resting against a washer 44 which is secured to the top end of shaft 30. The force of spring 42 operates to maintain frames 12 and 14 in the relative positions shown in FIG. 2.

Referring to FIG. 1 again, side member 16 of base frame 12 is formed with a cam slot 46 which is shown partially in dotted lines. The opposite side member 18 is provided with an identical cam slot (not shown). The lower end of side member 34 is formed with oppositely bent ears 48 and 50 and side frame 52 is provided with similarly formed ears, one of which is shown in dotted lines in FIG. 2 at 52. These ears function to maintain the frames 12 and 14 in proper alignment during the printing stroke of the stamper 10. A carrier 54 is rotatably supported on rod 56 which extends through both cam slots formed in side members 16 and 18 as well as through a slot 58 formed in side member 34 and a corresponding slot formed in side member 32 (not shown) and is secured in position by suitable means such as a retainer pin 60. Carrier 54 supports a plurality of printing belts, one of which is shown at 62. Each printing belt is constructed from a flexible material such as rubber and is formed with a variety of printing elements of indicia such as at 64. Each belt 62 is mounted at one end about a rotatable drum 66 which can be rotated to move the desired printing indicia on each belt 62 over the distal end of the carrier 54 as at 65.

When the stamper 10 is not in use, the printing indicia in the position at 65 would be rotated clockwise as viewed in FIG. 1 and would be urged upwardly into engagement with the underside of cross member 20. With

the pads 24 and 26 in engagement with the surface of an article to be stamped, by applying downward pressure on the movable frame 14, the printing carrier 54 and the printing elements carried will thereon both be moved downwardly and rotated about an axis parallel to the axis of rod 56 so that the printing elements 64 in the position shown at 65 will move through a generally arcuate path indicated by the arrows in FIG. 1 extending from the underside of cross member 20 and terminating at the surface of the article 28.

The foregoing has been a description of a conventional hand stamper wherein it has generally been the practice to locate an inked pad on the underside of cross member 20 so that, when the stamper is not in use, the printing elements on the distal end of the carrier 54 would be pressed into the pad.

The improved inking pad holder of the present invention as illustrated in FIG. 1 consists of an angled, substantially rectangular plate 68 which may be constructed from any sturdy resilient material such as 20 spring treated stainless steel.

Referring to FIG. 2, the top edge 70 of plate 68 is provided with notches 72 and 74 and the lower edge 76 is provided with similarly located notches 78 and 80.

25 The respective notches are spaced apart on each edge 70 and 76 so that they may engage the edges of side members 16 and 18 when the plate 68 is mounted on base frame 12.

30 A generally rectangular slot 82 is formed in plate 68 intermediate the edges 70 and 76 and extends generally parallel to the edges 70 and 76. The width of the slot 82 is 111 mm and the length of slot 82 is 30 mm.

82 should be formed so that a felt pad 84 maybe forced therethrough and frictionally engaged by the edges of the slot as shown in FIG 1 so that one end of the pad 84 will be held in a fixed position while the opposite end of the pad 84 will intersect the arcuate path of the printing elements on the printing belt 62 mounted on carrier 54.

40 The plate 68 is preferably manufactured from a resilient material so that it can be easily mounted on base frame 12 by slightly compressing the plate member to bring the edges 70 and 76 closer together so that when the plate member is mounted on the base frame 12 a slight spring force will be exerted in opposite directions on cross member 20 and bottom plate member 22.

One of the chief advantages of this arrangement is that the pad holder 6 can be easily removed from the hand stamper when it is necessary to resupply the pad 84 with ink or to gain access to the printing belts for the purpose of changing the indicia or cleaning the belts.

It is not necessary that the plate take the angled shape illustrated in FIG. 1 since it is only necessary that the plate position the inking pad so that one edge of the pad intersects the arcuate path of the printing indicia. In FIG. 3, for example, there is illustrated an arcuately shaped plate 86 having notches along its top and bottom edges similar to the notches formed in plate 68 in the embodiment illustrated in FIGS. 1 and 2 and with an inking pad 84' similarly positioned in a slot 88 formed intermediate the top and bottom edges of the plate. This embodiment is useful where the arcuate path of the distal end of the print carrier moves through an arc of greater radius than that of the hand stamper illustrated in FIGS. 1 and 2.

65 By positioning the inking pad to one side of the arcuate path of the printing elements, the pad will be flexed upon each printing stroke of the stamper so that, in the

event that the stamper has not been used for a period of time resulting in the stiffening of the inking pad, the pad may be easily restored to its soft condition by simply operating the stamper a few times to flex the pad and loosen its fibers. Such flexing also is effective to redistribute the supply of ink provided the pad has not completely dried out.

In comparison test, it has been found that the arrangement of the present invention will provide a substantially greater number of clear impressions when supplied with the same quantity of ink than a stamper where the pad is located on the underside of the cross member 20.

While the foregoing description relates to a preferred embodiment of the present invention it will be understood that various changes and modifications may be made therein without departing from the spirit and scope of the invention as defined in the appended claims.

What is claimed is:

1. An inking pad holder for self-inking stampers of the type having a frame including spaced side walls and generally parallel upper and lower end plates extending transversely of and connected to said side walls, carrier means movably mounted on said frame for supporting at least one printing element, said printing element being movable along a path between a deactuated, non-printing position and an actuated, printing position in response to movement of said carrier means with respect to said frame, said pad holder comprising a resilient plate member having first and second generally parallel edge portions with recesses formed therein spaced apart a distance substantially equal to the distance between said side walls, said plate member having a longitudinal dimension between said first and second edge portions that is greater than the distance between said upper and lower end plates on said frame so that, when said plate member is arcuately deformed, said recesses will engage said side walls of said frame adjacent their intersection with said upper and lower end plates, said plate member having means for supporting an inking pad with one portion of the pad positioned out of the path of travel of said printing element and fixed relative to said frame and with another portion of the pad intersecting said path so that said printing element will come into contact with said other portion of the pad at said intersection as said printing element moves along said path between said deactuated and actuated positions.

actuated positions.

2. The inking pad holder as claimed in claim 1 wherein said inking pad supporting means comprises an elongated slot having two elongated sides extending generally parallel with said edges of said plate member, said slot being formed in said resilient plate member at approximately the midpoint of said plate member, and the distance between said elongated sides of said slot being such that at least a portion of said inking pad will be frictionally engaged therebetween.

3. The inking pad holder as claimed in claim 2 wherein said inking pad is rectangular in cross section and has length width and height dimensions whereby when one end of said pad is inserted into said slot, the other end thereof will intersect said path of travel of said printing element where said pad holder is mounted on said frame.

4. An inking pad for self-inking stampers of the type having a frame including spaced side walls and generally parallel upper and lower end plates extending transversely of and connected to said side walls, carrier means movably mounted on said frame for supporting at least one printing element, said printing element being movable along a path between a deactuated, non-printing position and an actuated, printing position in response to movement of said carrier means with respect to said frame,

said pad holder comprising a resilient plate member having first and second edge portions, said edge portions having attachment means for attaching said edge portions of said plate member to said frame, said plate member having a longitudinal dimension between said first and second edge portions that is greater than the distance between said upper and lower end plates on said frame so that, when said plate member is arcuately deformed, said attachment means will engage said frame member adjacent the intersection of said side walls with said upper and lower end plates, said plate member having means for supporting an inking pad with one portion of the pad positioned out of the path of travel of said printing element and fixed relative to said frame and with another portion of the pad intersecting said path so that said printing element will come into contact with said other portion of the pad at said intersection as said printing element moves along said path between said deactuated and actuated positions.
